UNITED STATES PATENT OFFICE.

JOSEPH GIDEON MONCUS, OF CROWELL, TEXAS.

SHEARS.

No. 845,881.

Specification of Letters Patent.

Patented March 5, 1907.

Application filed January 9, 1906. Serial No. 295,280.

To all whom it may concern:

Be it known that I, JOSEPH GIDEON MONCUS, a citizen of the United States, residing at Crowell, in the county of Foard and State of Texas, have invented new and useful Improvements in Shears, of which the following is a specification.

This invention relates to shears, and more particularly to an implement of this kind designed for heading kafir-corn, sorghum, broom-corn, and the like, which is harvested by removing the heads or tops, and also for picking fruit and pruning.

The object of the invention is to provide shears which, when in use, are fastened to the hand and are operated by the thumb and index-finger, whereby the other fingers are left free to hold the object to be cut.

A further object is to obtain a draw cut.

20 The invention consists in certain novel features of construction hereinafter described, and claimed, and shown in the accompanying drawing, in which—

Figure 1 is a perspective view showing the shears open. Fig. 2 shows them closed. Fig. 3 shows the manner in which the shears are used.

Referring specifically to the drawings, 5 and 6, respectively, denote the blades of the shears, which are connected at their rear ends by a spring, whereby they are made self-opening when pressure on the blades is removed. The spring is also shaped so that the blade 5 will make a draw cut, as will be explained hereinafter.

The spring extends laterally from the back of the blade 5, as at 7, and at the end of this part a sharp bend 8 is made, from which the spring extends, as at 9, to the blade 6, that 40 end of the spring which joins this blade being bow-shaped, as at 10. The parts 7 and 9 give the spring a V-shaped offset portion which extends outwardly beyond the back edge of the blade 5. When the shears are closed, the blade 5 swings rearwardly, the bend 8 acting as a sort of a hinge, so that said blade is given a lengthwise movement to produce a draw cut. The cutting edge of the blade 5 is straight and that of the blade 6 is 50 slightly concave, which increases the effectiveness of the cutting action. The back

edges of both blades have a stiffening-bead 11 to prevent flexion.

The rear end of the blade 6 has a finger 12, which extends alongside said blade. The blade 5 works in the space 13 between the finger and the blade 6, so that the cutting edges of the blades are held closely together. The finger strikes the bead 11 on the blade 5, when the shears are closed, and thus also 60 serves as a stop to prevent excessive closing movement of the blades.

In use the shears are fastened to the thumb and index-finger and are operated by the movement of said fingers, which leaves the other fingers free to hold the object to be cut off, as clearly shown in Fig. 3. The shears will be made right and left handed, so that one can be placed on each hand. The blade 5 is made fast to the index-finger and the blade 70 6 to the thumb. The fastening means comprise rings 14, through which the fingers are extended. The rings are secured to the blade by set-screws or other suitable means 15, so that they can be adjusted on the blades 75 to suit the operator's hand. The front end of the blade 5 is shaped to form a support 16 for the tip of the index-finger, and the front end of the blade 6 is shaped to form a screw-driver 17, which can be used for the set-screws 80 15. The screw-driver of the right-handed shears will operate on the set-screws on the left-handed shears, and vice versa.

I claim—

1. An implement of the kind stated comprising a pair of blades, and a spring connecting the blades, said spring being extended angularly and in the same direction from the rear ends of the opposite blades and united at an acute angle offset from the blades. 85

2. An implement of the kind stated, comprising a pair of blades, and a bowed spring connecting the rear ends of the blades and offset angularly from the back of both blades in substantially the same direction. 90

In testimony whereof I have signed my name to this specification in the presence of two subscribing witnesses.

JOSEPH GIDEON MONCUS.
